UNITED STATES PATENT OFFICE.

JOB HUTCHINSON, OF NEW YORK, N. Y., ASSIGNOR TO NATIONAL INDICATOR COMPANY, A CORPORATION OF NEW YORK.

BEATER FOR MAYONNAISE DRESSING AND THE LIKE.

1,071,747.

Specification of Letters Patent.

Patented Sept. 2, 1913.

Application filed August 22, 1911. Serial No. 645,454. Renewed November 30, 1912. Serial No. 734,426.

To all whom it may concern:

Be it known that I, Job Hutchinson, a citizen of the United States, residing at Cropsey Avenue Bay 34 St., in the county 5 of Kings, city and State of New York, have invented new and useful Improvements in Beaters for Mayonnaise Dressing and the Like, of which the following is a specification.

10 It is well known that in making mayonnaise dressing and the like a great amount of beating is required while certain ingredients are very slowly added, since otherwise the product is inferior.

15 The general object of this invention is to provide devices which will greatly reduce the time and labor required in making such dressings, without lowering the quality of the product, and which are also quite capable of use for analogous beating, generally. With this object in view, I provide an inexpensive and effective apparatus which includes with beating devices means for supplying oil automatically at such rate 25 that each drop of oil is thoroughly incorporated with the other ingredients while the operation is very rapid and the labor slight.

20 In the accompanying drawings, Figure 1 represents a vertical axial section of the entire apparatus. Fig. 2 shows the devices as seen from the left in Fig. 1, the bowl shown in that figure being omitted. Fig. 3 is a perspective view of one of duplicate 35 beating devices.

30 In these views, A represents a bowl and B a cover therefor, both being of material, such as glass, for example, not easily corroded. Upon the cover is fixed an upwardly extending frame, C, of arched form having at one side of its upper portion a vertical disk, C', and at the crown of the arch a dependent boss or lug D provided below with two slightly divergent perforations to receive the branches of a rod E bent to approximately U-shape and having its lower connecting segment flattened to rest upon the bottom of the bowl. The lug is cut away at D', on opposite sides, to form 40 recesses which extend inward beyond the

line of the perforations, so that the rod branches may be bent out of alinement and be thus rigidly fixed in the perforations or sockets, after the parts have been assembled. Upon these branches, respectively, just below the lug, are revolvably mounted two equal engaging pinions G, one of which is engaged by a relatively large gear H provided with a handle H' and revolvably mounted upon a suitable stud projecting 45 from the center of the disk C'. The gear is provided with a very large hub H² which fits closely against the face of the disk and holds the gear exactly in the proper plane so that there can be no slipping in its engagement with its pinion, and between the meeting faces of the two members, which are formed with suitable races, are placed bearing balls to lessen friction. Each pinion operates a beating device made up of 50 two metal strips I and J, the longer strip, I, being perforated at its middle and provided with an eyelet M passing over the rod E and serving as a lower bearing, and also perforated near each end. The shorter strip J is similarly perforated, bent into the form of a hoop with the end perforations below and in registry, and is then slipped over the same branch of the rod E, the two upwardly extending portions of the strip I 55 passing through slots L in the widened middle portion of the strip J, whereby the two strips are held in perpendicular planes and the branches of the strip I are kept at a fixed distance apart. Below the slots, the parts of the strip I are curved outward to 60 form a nearly complete hoop of the same diameter as the other. The upper portions of the strip I are bent sharply inward to lie between two lugs K upon the lower face 65 of the corresponding pinion, the rod E passing through the registering holes in the overlapped strip ends and also through the pinion into its socket in the lug. The rod being then bent out of alinement as before 70 suggested, the parts are permanently held together, although separable by forcing the bent portion of the rod outward. The companion beater is assembled in the same way, care being taken, of course, to have the sec- 75 100

and pinion so engaged with the first that the hoops of one beater always lie in a different plane from those of the other beater.

The cover B is provided with a central opening surrounded by an upwardly extending flange, and through the opening the two beaters pass downward to the bottom of the bowl. The cover is also provided with an oil cup, O, having in its bottom a small aperture O' leading into the bowl. The bottom of the interior of the bowl has a relatively small depression so formed that its walls conform rather closely to the paths of the lower halves of the four rotating hoops. Obviously, this relatively small depression is surrounded by an annular, inwardly inclined, shelf-like portion of the larger body of the receptacle, and this portion is adapted to support the entire mass of beaten material, even when all the liquid has been beaten into non-flowing condition outside of rather than above the depression and the beaters. It is also evident that if any liquid separates from the beaten material so supported, it will at once drain back into the depression, to be further beaten; and further, that rapid rotation of the beater does not cause the liquid to be forced up along the outer wall of the upper portion of the receptacle to the cover joint but throws it, tangentially to the curved lateral wall of the depression, against the cover at some distance within its margin, thus avoiding leakage around the cover. Owing to the transparent character of the vessel and cover, the absence of liquid in the depression, as the operation reaches its final stage, may be observed, and in fact the cover and beaters may be lifted and the presence or absence of liquid in the depression may be determined by direct view. The rod E and all the strips are formed of "Monel metal" or nickel silver.

In use, the proper materials being placed in the depression in which the beaters lie and oil being placed in the cup, the gear is rotated imparting rapid movement to the pinions which by means of their lugs compel the two sets of beating hoops to rotate in opposite directions upon the branches of the rod E. The foamy product formed collects in the large space Q in the part of the bowl above the depression in which the ingredients are placed. The speed of rotation may be proportional to the discharge of the particular oil used, this depending to some extent upon its character and upon the temperature. If desired, this discharge may be regulated by means of a rod P so formed as to decrease the discharge as the rod is depressed.

What I claim is:

1. The combination with a beater receptacle having in its bottom a relatively small

central depression with curved lateral walls 65 continuous with the annular surrounding portion of the bottom for containing the material to be beaten, of a cover for the receptacle, and a beating device depending from the cover and rotating in close proximity to said walls.

2. The combination with an upwardly open beater receptacle having its walls carried rapidly outward at some distance above its lowest central point to form an annular, 75 shelf for supporting beaten material, of a cover for the receptacle, and a central rotary beater borne by the cover, extending approximately to said point, and operating within and below the material supported by 80 said shelf.

3. The combination with an incorrodible bowl and a cover for the bowl, of a rigidly attached frame projecting upwardly from the cover, a rod bent to U-shape, extending 85 through the cover to the bottom of the bowl, and having the upper ends of its branches fixed in said frame, mutually engaging pinions revolvably mounted upon the upper portions of said branches, respectively, means 90 for rotating the pinions, and beater devices revolvably mounted upon said branches, respectively, and each engaging and rotating with the corresponding pinion.

4. The combination with a bowl and its 95 cover, of a frame mounted upon the upper side of the cover, a rod bent to U-shape and extending through an opening in the cover into the bowl and having the upper ends of its branches fixed in said frame, hoops revolvably mounted upon the lower ends of said branches, respectively, elongated loops extending through slots in the upper portions of said hoops in a plane perpendicular to the plane of the latter and bent below into similar 105 hoops, pinions engaging the upper ends of the elongated loops to rotate them, and means for rotating the pinions.

5. The combination with a transparent beater receptacle having a relatively small 110 central depression in its bottom to receive the liquid to be beaten, of a transparent receptacle cover provided with an integral cup for discharging oil directly into the receptacle, and a rotary beating device secured to the cover and extending into said depression when the cover is in place; whereby the liquid thrown up by rapid beating strikes the cover within the line of its contact with the receptacle and the beaten 115 material remains undisturbed by the beating in an annular mass surrounding the depression.

6. In apparatus of the class described, the combination with a pinion and means for 120 rotating the same, of a hoop at some distance below the pinion with its diameter coinciding with the pinion's axial line, a sec-

ond hoop having the same diametrical vertical axis as the first and provided with arms passing through the upper portion of the first and fixed to said pinion; whereby the two hoops are compelled to rotate together and to maintain a fixed angular distance from each other, while distortion of either is prevented.

In testimony whereof I have hereunto set my hand in presence of two subscribing witnesses.

JOB HUTCHINSON.
